CHILD'S SPRING CHAIR

Bert F. Strand, Jr., Toledo, Ohio

Application June 9, 1947, Serial No. 753,399

4 Claims. (Cl. 155—54)

1

This invention relates to chairs for use by small children, and has for its object the provision of an improved chair of this type of spring frame construction and adapted for use in the home or on automobile seats.

Another object of the invention is the provision of a chair of this character which may be permitted to have a springing action or be braced against such action by simple and efficient means for the purpose.

Another object of the invention is the provision in a chair of this character of a bail member attached to the upper portion of the chair and adapted to be placed in raised upright position to serve as a carrying member for the chair, to be placed in rearwardly projecting substantially horizontal position to be used as a member to be grasped and moved forward and backward to a slight extent to impart a slight vibratory or springing movement to the chair, and to be placed in downwardly, rearwardly inclined position and engaged at its loop or free end with the foot or bottom portion of the chair to brace it against springing action.

The invention is fully described in the following specification, and a preferred embodiment thereof is illustrated in the accompanying drawings, in which—

Fig. 1 is a rear perspective view of a chair embodying the invention, with the bail member in frame bracing position and indicated in dotted lines in other positions of its swinging movement; Fig. 2 is a front perspective view of the chair with the bail member in raised or upright position and indicated in dotted lines in other positions of its swinging movement; Fig. 3 is a front perspective view of the chair similar to Fig. 2, with the tray removed and with the bail member in frame bracing position, and Fig. 4 is a bottom perspective view of the tray removed from the chair.

Referring to the drawings, 1, 1 represent the two duplicate transversely spaced or opposed side members of the chair frame which are of spring material, preferably strap steel, and each is bent or shaped to provide a rearwardly extending runner or foot portion 2, a front upright portion 3 and a rearwardly extending arm portion 4. The runner portions 2 of the two members are connected and rigidly braced apart by a cross-piece 5 attached thereto. The arm portions 4 are connected and braced at their rear ends by a back 6, such end portions being preferably transversely turned to present flat vertical faces to the respective side edges of the back so as to facilitate

2

attaching, as shown. The upright portions 3 are connected and braced substantially midway of their ends by a seat 7 the front edge of which is fixedly attached to each upright, as at 8, and its rear edge is suspended from the lower edge of the back 6 by a flexible strap 9 of leather or other suitable material.

The runner portions 2 are preferably slightly upwardly bowed to make contact at their ends only with the floor or other member on which the chair may rest, and a shoe 10 of rubber, plastic or other suitable material is preferably provided at the front end of each of such portions. The rear end of each runner is turned upwardly and over, as shown at 11, to provide an eye or loop with its front side open for the purpose hereinafter described.

A bail member 12 of U-form, and preferably of round bar stock, has the free ends of its legs turned in and pivotally engaged with sockets in bearing blocks 13 attached to the under sides of the respective arm portions 4 so that upon a lifting of the chair by the bail, the chair is held in balanced position. This bail member may be placed in upright position, as shown in full lines in Fig. 2, to facilitate carrying a chair or suspending it by a rope or other means connected to the bail to permit the chair to serve as a swing seat. The bail may also be rearwardly extended in horizontal position, as shown by dotted lines at a in Figs. 1 and 2, and thus serve as a handle to be grasped by a person seated near and moved to impart a reciprocatory springing or rocking movement to the chair to amuse a small child seated therein. The bail may also be swung down to the rearwardly inclined position shown in full lines in Figs. 1 and 3 and have the cross portion of its loop engaged with the loops 11 at the ends of the runners 2. This causes the bail to serve as a rigid brace between the top and bottom portions of the chair frame to prevent springing action of the frame. The bail is yieldingly held in upright position by the lower end of its legs springing into engagement with notches in lugs 14 at the outer edges of the arm portions 4. It is likewise yieldingly held in its horizontal position by the springing engagement of its legs within notched end portions 15 of said arms. The free or swinging end of the bail may be easily sprung into engagement with or released from the loops 11.

If the chair is to be placed on an automobile seat, the rear ends of the runners 2 are inserted between the seat cushion and rear cushion, thus tending to hold the chair on the seat and to pre-

vent forward tipping. To facilitate this, the rear ends of the runners 2 are curved slightly downward. Straps 16 may be attached to the ends of the cross-piece 5 and engaged around a small child in the chair to prevent it from slipping out under the tray.

A tray 17 may be mounted on the arms 4 and slidably held thereto by engagement of angle strips 18 with the arms. These strips are engaged with the inner arm edges by endwise insertion of the strips through notches 19 in said edges (Fig. 3). The tray is held in adjusted position on the arms by engagement of releasable hand operated bolts 20 on the under side of the tray with notches 21 in the arm edges.

It is apparent that I have provided a simple and novel form of spring frame chair for small children, which chair may be conveniently carried from place to place by use of the bail member when the latter is in upright position. The 20 bail member may also be used to rock or jiggle a child in the chair when the bail member is in horizontal position, or may be used to rigidly brace the chair-frame against springing movements when the bail member is in rearwardly and downwardly inclined position as when the chair is used as a high chair.

I wish it understood that my invention is not limited to any specific construction, arrangement or form of the parts, as it is capable of numerous modifications and changes without departing from the spirit of the claims.

Having thus described my invention, what I claim as new, and desire to secure by United States Letters Patent, is:

1. A chair of the class described comprising opposing side frame members, each constituting a single piece of spring metal having a front upright portion with a rearwardly extending runner portion at its lower end and a rearwardly extending arm portion at its upper end, a back disposed between and attached to the rear ends of the arm portion, a seat attached to and projecting rearwardly from the upright portions intermediate their ends and suspended at its rear edge from the back, and bail means connecting said arm portions to the rear ends of said runner portions and serving to limit the springing action of the frame members.

2. A chair of the class described comprising opposing side frame members of spring metal each having a front upright portion, a rearwardly extending runner portion at its lower end and a rearwardly extending arm at its upper end, means rigidly connecting said frame members and including a back attached to the rear ends of the arm portions and a seat attached to and projecting rearwardly from said upright portion 10 and connected to the back, and a bail member straddling the frame members at the outer sides of the arm portions and pivotally connected thereto for vertical swinging movements rearwardly and downwardly from upright carrying 15 position to intermediate and lower positions, and means for releasably engaging said bail when in lower position with the rear end portions of the runners to brace the frame members against springing movements.
- 20 3. An arrangement as called for in claim 2, together with separate means on said arm portions to engage and releasably hold the bail in either upright or intermediate positions.
- 25 4. In a chair having opposed spring side frame members with vertically spaced upper and lower rearwardly extending yieldingly connected portions and cross-connecting means for said portions, a bail pivoted to said upper portions for forward and rearward swinging movements in a 30 vertical plane and adapted when in upright position to serve as a suspending member for the chair and when swung downward rearwardly of the chair to engage the rear ends of said lower portions to limit the spring of the side frame 35 members, and means on the rear ends of said lower frame portions for releasable holding engagement with the bail when the two are in engaged relation.
